UNITED STATES PATENT OFFICE

2,681,500

METHOD OF MANUFACTURING TURBINE
OR THE LIKE BLADESFrederick William Whitehead, Bristol, England,
assignor to The Bristol Aeroplane Company
Limited, Bristol, England, a British company

Application July 3, 1950, Serial No. 171,958

Claims priority, application Great Britain
July 18, 1949

3 Claims. (Cl. 29—156.8)

1

This invention concerns methods of manufacturing turbine or the like blades (more particularly for gas turbine engines) having a shroud which form a part of a built-up shroud ring when the blades are assembled side by side. For convenience such blades are referred to hereinafter as "shrouded blades."

There are, broadly speaking, two main types of blades, namely, solid blades and hollow blades, the former being characterised by a substantially solid vane portion (though it may have relatively small channels or passages extending therethrough) and the latter being characterised by a vane having a relatively thin wall, for example, being fabricated from sheet metal. The present invention is concerned with solid blades as just defined (hereinafter referred to throughout the specification simply as solid blades) and does not relate to hollow blades.

The present invention has for its object to provide an improved method of making shrouded blades where it is impossible or inconvenient to form the shroud when producing the blade shank.

More specifically this invention has for its object to form a shroud on the concave face of a blade subsequently to the production of said face.

A further object of the invention is the provision of a shroud on the concave face of the blade which is integral with the blade shank i. e. is not separately formed and subsequently united to the blade by welding or in any other way.

According to the present invention a method of manufacturing shrouded, solid, metal blades of aerofoil shape in cross section comprises bending over the tip end of the blade and forming a shroud or a part of a shroud from the bent-over portion.

The blade may be rough machined or finish machined prior to bending the tip end to form the shroud and the term "machined blade" as used hereinafter is to be understood as including both the partly and completely machined blade.

According to a feature of the present invention a method of manufacturing shrouded, solid, metal blades of aerofoil shape in cross section comprises forming a shroud portion integral with, and projecting substantially at right angles to, the convex surface inwardly of the tip of the blade at the same time as said surface is produced, forming a concave surface which extends beyond said shroud portion to form a tip portion of the blade, bending the tip portion to lie substantially in the plane of said shroud portion and projecting from the concave surface and shaping the bent-over tip portion and said shroud portion to form a blade shroud.

2

In a gas turbine engine the thermal and mechanical stresses in the blades greatly limit the range of materials which may be used in making the blades. In order to achieve the required mechanical strength the blades may be machined from a solid work-piece—either from a bar of material or from forging.

In the specification accompanying application No. 7,501/47 there is described a machine for forming the convex surface of a turbine blade from a bar of material and in the specification accompanying application No. 7,628/47 there is described a machine for producing the concave face of unshrouded blades from a bar of material. The present invention makes use of the machines described in said applications and is concerned with forming a shroud from the machined blade by bending the tip end of the blade and thereafter shaping it in any convenient manner to the form required for the blade shroud.

Practical applications of the present invention will now be described, by way of example only, with reference to the accompanying drawings, whereof:

25 Figure 1 is a diagrammatic sectional elevation of the means for forming the concave face of a solid, metal blade of aerofoil shape in cross section.

Figure 2 is a plan view of Figure 1,

30 Figure 3 is a diagrammatic sectional elevation of the means for forming the convex surface of a solid metal blade of aerofoil shape in cross section,

Figure 4 is a plan view of Figure 3,

35 Figures 5, 6, 7, 8 and 9 show various steps in the formation of the shroud by bending and shaping the tip of the blade,

Figures 10 and 11 show two steps in the formation of an alternative construction of shroud by bending and shaping the tip of the blade, and

40 Figure 12 is a side view of a finished blade made as described with reference to Figures 1-9 of the drawings.

45 Referring to Figure 1, the blade is produced from a bar of material 20 which is suitably held in a carrier generally indicated at 21. To impart the required shape to the concave surface of the blade there is provided a cutter or a grinding wheel 22 which is carried and driven by a shaft 23.

The grinding wheel or cutter 22 is of conical form and is fed into the blade in the direction of the arrow 24 and having completed this movement the wheel is then moved across the blade in a transverse direction about an axis 25 (Figure 2) which is inclined with respect to the axis of rotation of the shaft 23 i. e. the wheel or cut-

3

ter 22 is given a conical motion the apex of which is near the free end of the wheel. In this way the required concave surface 26 is formed on the bar 20. When the concave surface is produced by the machining operation described it is not possible to form a shroud on the concave surface 26 during said operation.

The bar 20 with the concave surface 26 is then mounted on a machine to form the convex surface 28. The machine for forming the convex surface is diagrammatically illustrated in Figures 3 and 4 to which reference will now be made. The bar 20 is held in a carrier 29 so that it is movable in the direction of arrow 31 to engage a grinding wheel 30. The grinding wheel 30 has a face width less than the height of the bar and is mounted on a shaft 33 the axis of rotation of which is approximately parallel to the longitudinal axis of the bar 20. The carrier 29 is supported by a shaft 34 which is rotatably mounted in bearings 35 and there is a handle 36 for oscillating the shaft and hence the carrier 29. The assembly of the carrier 29 and its driving means is mounted on a slide 37 for movement towards and away from the grinding wheel 30. The shaft 34 carries a cam 38 which engages a follower 39 carried by a frame member 40. A spring 41 is provided to hold the cam in engagement with the follower 39 and to draw the bar towards the grinding wheels 30, 31. The machine shown in Figures 3 and 4 is more fully described in the specification accompanying application No. 7,501/47 and it is to be understood in the accompanying drawings the machine is diagrammatically shown.

While the grinding wheel 30 is being driven the handle 36 is oscillated whereby the bar 20 is oscillated in the direction of arrow 43 about axis 44 and, at the same time is reciprocated relatively to the grinding wheel 30, in the direction of arrow 45 so that the required convex surface 28 is formed on the bar.

The blade so far produced has, as shown in Figure 3, a thickened tip portion and this part is then rough milled to remove the metal as shown in chain dotted lines. It will be noted that a shroud part 42, integral with surface 28, is left a short distance in from the blade tip. When making the shroud part 42 sufficient metal is left for a final machining operation after the shroud has been formed as will shortly be described.

The form of the blade produced by the machining operations described above will be apparent from Figure 5 and it will be noted that the bar 20 has been formed with a blade shank 46 having concave and convex surfaces 26, 28 respectively. The bar 20 will subsequently be machined to form the blade attachment portion. It is to be understood that the method and apparatus for forming the concave and convex surfaces described are given by way of example only and other procedures may be followed.

As shown in Figure 5 the blade is gripped between anvil members 47, 48 which are accurately shaped to fit the surfaces 26, 28 respectively. The members 47, 48 are carried by any convenient form of adjustable gripping device 49. The tip portion of the blade is heated either before it is clamped between the anvil members 47, 48 or, as shown in Figure 5, while it is so held. The tip portion of the blade is then hot forged so that it is bent on to the surface 50 of the anvil member 47. The surface 50 is shaped so that with the hot forging operation that part of the tip

4

portion 27 which is engaged thereby will have the required shape imparted to it. Figure 7 shows the tip portion 27 at the end of the hot forging operation and it will be noted that it has been bent over so as to lie substantially in the plane of the shroud 42. Following the hot forging operation the edges of the parts 27 and 42 are ground as shown in Figure 8. The edges 51 are shaped by a grinding wheel 52 and the edges 53, 54 are similarly shaped by a grinding wheel 55. Referring to Figure 9, the blade is thereafter suitably mounted so that the outer peripheral surface 56 is ground by wheel 57 to the required cylindrical curvature.

The final product (Figure 12) is a blade having a shroud 58 which is made up from the tip portion 27 and the shroud portion 42 both of which are integral with the blade shank 46.

In the alternative arrangement shown in Figures 10 and 11 the concave surface is formed as described with reference to Figures 1 and 2. The convex surface is formed generally as described with reference to Figures 3 and 4 with, however, a single grinding wheel so that the shroud 42 is not produced. The tip portion of the blade 27 is longer than in the construction shown in Figure 5. The tip portion 27 is hot forged in the manner described above and is thereafter ground to final shape and the shroud 60 which is finally produced extends entirely to one side of the blade shank 46 and is of such length as to abut the tip end of the shank 46 when the blades are mounted in the turbine.

Although it is preferred that a hot forging operation be used to bend over the tip of the blade, this may be done by a cold forging operation.

Furthermore, although the operation of bending over the tip of the blade has been satisfactorily carried out by hand hammering, it is to be understood that the tip of a blade may be automatically bent in a machine.

I claim:

1. A method of manufacturing shrouded, solid, metal blades of aerofoil shape in cross-section which comprises securing a blade blank at one end, grinding the blank to form the convex and concave sides of the blade, the shape of the concave surface so produced extending to the free end of the blank, machining the free end of the blank on the convex side of the blade to form an extended tip portion of the blade and a shroud projecting substantially at right angles from the convex side of the blade, subjecting said tip portion to a hot forging process whereby said tip portion is bent over to lie substantially in the plane of said shroud portion and projecting from said concave surface to form with the shroud portion a shroud for the blade, the underside of said bent over tip portion being shaped during said hot forging process, and grinding the edges and outer surface of the blade shroud to the required shape.

2. A method of manufacturing shrouded, solid, metal blades of aerofoil shape in cross-section which comprises machining one side of a blank to form a concave side of the blade extending from the root through the free end of the blade, machining the opposite side of the blank to form a convex side of the blade extending from the root to a point short of the free end of the blade, whereby a thickened tip portion is left at the free end having a concave surface produced as a continuation of said concave surface of the blade, removing a part of the thickened tip portion on the convex side of the blank to form the

tip of the blade and a shroud portion integral with and projecting substantially at right angles from the convex side of the blade, bending over said blade tip to lie substantially in the plane of said shroud portion and projecting from said concave side of the blade, and shaping the bent-over blade tip and said shroud portion to form the blade shroud.

3. A method of manufacturing shrouded, solid, metal blades of aerofoil shape in cross-section which comprises machining a blank on opposite sides to form the convex and concave sides of the blade, so that the concave side extends from the root to the free end of the blade and the convex side extends from the root to a point short of the free end of the blade, whereby a thickened portion is left at the free end, machining the thickened portion of the blank at the free end of the blade and on the convex side to form an extended tip portion of the blade having a concave surface formed as a continuation of the concave surface of the blade and leaving a shroud portion projecting substantially

5 at right angles from the convex side of the blade, bending over said tip portion to lie substantially in the plane of said shroud portion and projecting from said concave surface of the blade, and shaping the bent over tip portion and the shroud portion to form the blade shroud.
